(57) **CLAIM**

The ornamental design for an end fastener for an eyeglass retainer, as shown and described.

DESCRIPTION

FIG. 1 is a pictorial view of the front and top of an end fastener showing my new design;

FIG. 2 is a top plan view of the fastener, the bottom being a mirror image thereof;

FIG. 3 is a front elevational view thereof;

FIG. 4 is a left end elevational view thereof;

FIG. 5 is a right end elevational view thereof; and,

FIG. 6 is a back elevational view thereof.

The broken lines in FIGS. 1, 2, 3, and 6 show a portion of an eyeglass retainer cord to which the fastener of the invention is attached. The cord is not part of the design.
